ALEYNE G. BRADLEY, OF BALTIMORE, MARYLAND, ASSIGNOR TO CRIPPEN & REID, OF BALTIMORE, MARYLAND, A CORPORATION OF NEW YORK.

ADJUSTABLE DRESS.

1,294,037.

Specification of Letters Patent. Patented Feb. 11, 1919.

Application filed November 8, 1916. Serial No. 130,245.

To all whom it may concern:

Be it known that I, ALEYNE G. BRADLEY, a citizen of the United States, residing at Baltimore, in the State of Maryland, have 5 invented certain new and useful Improvements in Adjustable Dresses; and I do hereby declare the following to be a full, clear, and exact description of the invention, such as will enable others skilled in the art to 10 which it appertains to make and use the same.

This invention relates to maternity dresses, and particularly to such a dress in which there is provided a unitary waist and 15 skirt portion, the dress being opened down the front along a line to one side of the center of the dress and provided with a set of tucks which form a central panel.

It is one of the objects of the present invention to provide for the variation of the 20 girth or waist line of the dress in a neat and substantial manner without the formation of uncomfortable folds or plaits, and to provide a dress which is of practicable design, 25 neat in appearance, and readily adjustable as may be necessary.

Another object of the invention is to provide a dress of this kind in which the adjustment for the increase of the circumference 30 of the waist or its girth measurement may be readily accomplished and is positioned in the front portion of the dress so that the wearer may easily arrange the parts from the front and avoid the folding or creasing 35 of the dress and its adjustment at the rear.

With these and other objects in view the dress consists of an integral waist and skirt portion divided along a line which is located in the front from the neck to a point 40 somewhat below the waist line to permit the dress to be put on by adjustment over the head, and consists further in details of construction and arrangement of parts as will be more fully hereinafter described, and as 45 shown in the drawings, in which there is illustrated a preferred embodiment of the invention.

In the drawing:

Figure 1 is a perspective view of the dress 50 in its position as applied and with the girth or waist portion contracted to its minimum.

Fig. 2 is a perspective view from the front of the dress showing the parts arranged for an increase of the length of the waistband 55 line.

Fig. 3 is a perspective view of the dress with the upper front portion separated along the opening to clearly illustrate the edge and fold structure.

Fig. 4 is a partial detail sectional view 60 showing the front portion of the dress in position to be secured, and showing the disposition of the folds in this arrangement.

It is desirable to provide a maternity dress with means for facilitating the adjustment of the dress so that it may be readily loosened and fastened from the front and present a neat and attractive appearance in any of its folded or adjusted positions. In the present embodiment of the invention, 70 the dress A comprises an integral structure having a suitable waist portion 2 and skirt portion 3, the design of which obviously may be varied to suit the taste. Between the waist portion 2 and the skirt portion 3 there is disposed a waistband 4, and the front portion of the dress from the neck down to a point suitably below the waistband 4 is provided with an opening as indicated at 5, Fig. 3, disposed at one side of the center line of 80 the waist and skirt and continuing to a point somewhat below the waistband 4. The fullness of the body of the waist 2 may be gathered in as at the lines 6 on each side of the waist at a point terminating at the waistband 4, and one side of the dress as at 7. The edge 7 is provided with a line of buttons or other suitable fastening devices 8 adapted to be engaged by complementary fastening means as buttonholes 9 formed 90 along the adjacent edge 10 of the front portion of the dress when this latter is folded over the edge 7 to close the front opening.

One of the important features of the present invention resides in the means for adjusting the dress at the waist line to provide or take up fullness as may be necessary, and in its preferred form this variation or adjustment of the waist line of the dress is accomplished by the structure of the dress at 100 the front thereof. In the preferred manner of securing this adjustment the dress is provided with a set of vertically and substantially parallelly extending tucks 12 and 13 suitably spaced along the front of the dress 105 and forming between them a central panel 14. These tucks are formed by a line of stitching 15 and 16 respectively, one for each tuck, the tuck 13 commencing at a point 17 near the top of the panel 14 at the 110

neck line and extending downwardly therefrom so as to form an intermediate foldable portion 18, Figs. 3 and 4, the tuck being adapted to overlap and cover the line of buttonholes 9 in the edge 10 of the dress, and having at a point in the vicinity of the waist line a button hole 19. Likewise the tuck 12 has at an opposite point a buttonhole 20, the buttonholes 19 and 20 respectively being adapted for connection with one or another of a series of buttons 21 and 22, Figs. 2 and 3. These series of buttons are disposed in this embodiment upon the waistband 4, although it is understood that the latter may be omitted and the series of buttons 21 and 22 fastened upon the body of the dress at about the waist line. While the buttons 21 and 22 and their respective buttonholes 19 and 20 may form a suitable means for securing the plaits 12 and 13 to the buttons, it is to be understood that any other suitable fastening may be provided as desired in substitution therefor.

To provide for the circumferential adjustment of the waist of the dress, the first button of the series 21 in Fig. 3 is shown as being disposed somewhat remotely from the line of stitching of the plait 12 so that there is provided an intermediate folding portion 12' which when the tuck 12 is to be fastened to one of the series of buttons 21 will fold inwardly and beneath the front panel structure as shown in Fig. 4. In like manner the intermediate portion 18 between the plait 13 and the edge 10 of the dress will fold inwardly along the plait 13 as shown in Fig. 4.

In the adjustment of the dress, if the wearer desires that it be contracted at the waist line to its minimum girth the plaits 12 and 13 are adjusted to overlap the series of buttons 21 and 22 and with buttonholes 19 and 20 arranged to engage the outermost of the series of buttons 21—22 therebelow, thus forming a long inward fold on each side of the central panel beneath the plaits 12 and 13. When these are buttoned in a position as indicated in Fig. 1 to their respective buttons, the front central portion 14 of the dress is drawn out smooth and flat to present a vertical panel portion with plaited or tucked marginal edges, thus making a continuous and neat frontal appearance, the material which has been taken up

folding inwardly under the front panel 14 as shown in Fig. 4 and being entirely concealed. 55 To secure an enlargement of the waist measurement the tucks or plaits 12 and 13 are disconnected from the outermost buttons and arranged on the next buttons in the row, or if desired at the innermost buttons as shown 60 in Fig. 2 in which condition of parts the underlying folds beneath the tucks or plaits 12 and 13 are let out to increase the girth of the dress, the plait 13 still serving to cover the edge 7 of the dress which is provided with the line of buttons 8 hereinbefore described.

From this it will be seen that the placket of the dress is arranged in the front and is at all times effectually covered by the overlying plait 13 which in turn covers the fly portion 10 of the edge of the dress when this is buttoned or fastened suitably along the edge 7.

It is to be understood that where the terms buttons and buttonholes have been used throughout this specification that the invention is not necessarily limited to this type of fastening, and that any other suitable type of fastening device may be utilized at the 80 different portions of the dress to be fastened one to the other, and also it is understood that the proportion of the parts and their design may be materially varied without departing from the scope of the invention and 85 within the limits of the appended claim.

What is claimed as new is:

A maternity dress combining a waist and skirt with a front panel having its vertical edges deeply plaited and an inner layer 90 turned upon one plait and forming a fly edge which is provided for attachment to the adjacent edge of the body of the garment along an opening extending from the neck to a point below the waist line; a set of fastening devices on each side of the body and along the waist line, the margins of the panel being provided for attachment selectively to respective fastenings of the sets to vary the 95 girth length of the waist.

In testimony whereof I affix my signature in presence of two witnesses.

ALEYNE G. BRADLEY.
